[57] **CLAIM**

The ornamental design for a pilothouse, as shown and
described.

DESCRIPTION

FIG. 1 is a top, front and right side perspective view of
a pilothouse showing my new design;

FIG. 2 is a reduced top perspective view thereof, the
broken lines are for illustrative purposes only and form
no part of the claimed design;

FIG. 3 is a right side elevational view thereof;

FIG. 4 is a front elevational view thereof;

FIG. 5 is a left side elevational view thereof;

FIG. 6 is a rear elevational view thereof;

FIG. 7 is a cross sectional view taken along the line
7—7 of FIG. 6;

FIG. 8 is a top plan view thereof;

FIG. 9 is a right side elevational view of a second em-
bodiment of the pilothouse; and,

FIG. 10 is a top, front and left side perspective view of
FIG. 9.
